(57) **CLAIM**

The ornamental design for a practice putting pad, as shown and described.

DESCRIPTION

My practice putting pad is used to improve a golfer's putting skill.

FIG. 1 is a top plan view of a practice putting pad showing my new design; and,

FIG. 2 is a side elevation view of the practice putting pad. The broken line showing of the circular portion on FIG. 1 is for illustrative purposes only and forms no part of the claimed design.
